SLIDER FOR SEPARABLE FASTENERS AND
THE METHOD OF MAKING SAMEWilliam R. Epes, Forest Hills, N. Y., assignor to
United States Rubber Company, New York,
N. Y., a corporation of New Jersey

Application April 5, 1940, Serial No. 327,978

7 Claims. (Cl. 29—148)

This invention relates to an improved slider for separable fasteners and the method of manufacturing same. The invention relates particularly to an automatic spring lock type of slider and an improved method of assembling the same.

The slider embodying this invention is particularly useful for operating separable fasteners for use in wearing apparel where it is desirable to prevent the strings of fastener elements from being disengaged and permit the garment to be accidentally opened. The invention is closely related to the slider disclosed in Patent No. 2,197,690, granted April 16, 1940, upon application Serial Number 308,755, filed December 12, 1939, in the name of Gilman M. Gay. It differs therefrom primarily in the improved construction which permits the slider elements to be assembled with greater ease. The improved construction comprises an opening formed in one of the wings of the slider body which is so designed in reference to the locking head that the head of a one piece ball and spring locking member may be pushed through the opening while the ball is arranged longitudinally of the wing, and then may be pushed rearwardly into its operative position with one other simple motion while the end of the ball is simultaneously brought into position to be secured to the slider body. The end of the ball is fixed in such position with its operating pull member and with its locking head resiliently retained in locking engagement with the fastener elements. The locking head may be disengaged therefrom by the pull member when the slider is moved.

The foregoing and other objects and features of this invention are described and shown more in detail in the following description and accompanying drawing, in which:

Fig. 1 is an isometric exploded view of the elements of the slider embodying this invention, and illustrating the method of assembling;

Fig. 2 is an isometric view of the slider, illustrating an intermediate step in the method of assembling the parts;

Fig. 3 is an isometric view of the assembled slider;

Fig. 4 is a front end view of the assembled slider;

Fig. 5 is a cross section of the slider taken on line 5—5 in Fig. 3, and showing in addition the cooperation between the locking head and the fastener elements;

Fig. 6 is a partial plan view of a modified form of the slider, illustrating a differently shaped

opening for the reception of the locking head; and

Fig. 7 is a modified form of the locking head adapted to cooperate with the opening shown in Fig. 6.

The slider comprises a body 10 having wings 11 and 12 and a spreader member 13 interposed therebetween at the front end of the slider. As shown in Fig. 1, the top wing 11 of the slider body 10 is provided with an opening 14 having an enlarged head 15 and a narrower elongated branch 16 extending therefrom and longitudinally of the wing 11 towards the rear end of the slider. The opening 14 is shown in the form of a T in which the head 15 of the T is adapted to receive the head 17 of the locking member formed on one end of a combination bail and spring locking member 18. The stem 16 of the T is adapted to retain the head 17 below the inside surface of the wing 11 when the head has been moved into its operative position.

The combination bail and locking member 18 is made from flat spring metal stock and shaped into the form of a U having the locking head 17 on one end, and an end 19 on the other end of the U which is adapted to be secured to the body 10 of the slider. The intermediate portion 20 of the bail 18 is arched for the reception of the lower end 21 of the pull 22, the pull being provided with an aperture 23 through which the intermediate portion 20 extends.

The front end of the slider is provided with a groove 24, or channel which extends perpendicular to the plane of the wings 11 and 12 and opens forwardly. The end 19 of the bail is provided with a notched out portion 25, which is adapted to be received by the groove 24, and when in position the shoulders 26 and 27, at each end of the notched out portion 25, are adapted to abut against the top and bottom ends 28 and 29 respectively of the groove 24.

The end of the ball 18 upon which the locking head 17 is formed has a neck or reduced portion 30 which connects the head 17 to the main body 45 of the bail 18, and is provided with shoulders 31 and 32 at each end. The head 17 is provided with a locking projection 33 which is adapted to enter between the fastener elements 35, as shown in Fig. 5, and lock the slider in any position at which it may be stopped. If desired the end of the projection 33 may be provided with a beveled edge 34 which extends upwardly and forwardly towards the front of the slider so as to permit the projection 33 to ride over the elements 34 without using the pull 22 to move the projection from

between the elements when the slider is moved forwardly to close the fastener.

In assembling the slider parts, the bail 18 is projected through the aperture 23 in the pull member 22, and such parts are then arranged as shown in Fig. 1, so that the bail 18 extends longitudinally of the wing 11 and the locking head 17 is over the head 15 of the opening 14 in the wing 11. In such position the end of the bail to be fixed in the slider will be arranged above and slightly to the front of the open side of the groove 24 in the slider body. The head 17 is then inserted by a vertically downward movement through the head 15 and stopped, so that the shoulder 31 will be above the wing 11 and the shoulder 32 will be below the wing. All of the parts of the bail 18 may be brought down parallel with the movement of the head 17, or the end 19, to be fixed in the slider, may be brought down after the head 17 has passed through the opening 15. In any event the notched out portion 25 of the bail 18 will be placed opposite the open side of the groove 24. When the bail 18 is in this intermediate position, which is shown in Fig. 2, it may be moved into its final position by a substantially straight rearward motion, so that the neck 30 will enter the stem 16 of the T-shaped slot and the notched out portion 25 will enter the groove 24, as shown in Fig. 3. When in such position the shoulders 31 at the locking end of the bail will rest upon, or be slightly spaced from the top surface of the wing 11, and the shoulders 32 will be below the bottom surface of the wing 11 and both shoulders 31 and 32 will overhang the edges of the stem 16 of the T-shaped slot. When the bail 18 is in such position the edges 36 of the groove 24 are beaded over the notched out portion 25 of the fixed end of the bail 18, and the shoulders 26 and 27, will then bear against the top and bottom ends 28 and 29 of the metal forming the walls of the groove 24. The end 19 of the bail will then be held in a fixed position so that the locking projection 33 will be resiliently held in locking engagement with the fastener elements 35 on their strings 37.

The projection 33 may be moved out of locking engagement with the elements 35 by moving the pull 22 rearwardly against the sloping end of the bail 18 and thereby move the slider, so as to open the strings 37 of fasteners by separating the elements 35. The pull 22 may be moved in the opposite direction to close the fastener by pulling upwardly to release the projection from its locking engagement, or in case the projection 33 is beveled the slider may be moved without the use of the pull. In order to reduce the clearance between the elements 35 and the wings 11 and 12, and provide space for the movement of the locking head 17, the head is beveled at 38 and the edges of the branch 16 of the opening are undercut or beveled at 39 to permit the head 17 to recede into the wing 11.

A modified form of the invention is shown in Figs. 6 and 7, in which a differently shaped locking head and opening in the slider wing for receiving same is shown. In Fig. 6, there is illustrated a fragmentary portion of a wing 11' having an L-shaped opening 14' for the reception of the locking head 17' formed on the locking end of a U-shaped bail 18' as shown in Fig. 7. Except for the shape of the locking head, the bail 18' is of the same shape as bail 18 shown in Figs. 1-5, and it cooperates with the slider body in the same way. The locking head 17' is provided with

a reduced neck portion 30' having top and bottom shoulders 31' and 32'. The head 17' is also provided with a locking projection 33' which is adapted to cooperate with the fastener elements 35. The head 17' is adapted to be inserted through the head 15' of the L-shaped opening 14', and moved forwardly into the stem 16' of the opening, in a manner similar to the insertion of the locking head 17' of the previously described modification. When the head 17' has been moved into position, and its opposite end has been fixed to the front end of the slider body, the locking projection 33' is resiliently held in its locking position between the fastener elements 35. The shoulder 32' will then be beneath the bottom surface of the slider wing 11' and will overhang the edge of the stem 16' of the opening 14', and the upper shoulders 31' will rest upon the top surface of the wing 11', or may be spaced slightly therefrom. In such position the locking projection 33' may be operated by the pull similar to that described in reference to Figs. 1-5.

It is contemplated that changes in the details of this invention may be made, and it is desired to claim the invention as broadly as permitted by the prior art and to the extent covered by the appended claims.

Having thus described my invention, what I claim and desire to protect by Letters Patent is:

1. A slider for a separable fastener comprising two wings and a spreader member interposed therebetween at their front ends, said wings and spreader being adapted to slide in contact with the fastener elements to engage and disengage same, said slider having a socket at its front end and an opening in one of said wings at its rear end, said opening having a transversely enlarged head and a narrower branch extending rearwardly therefrom and longitudinally of said wing, a one-piece flat spring metal combination bail and locking device having inwardly extending front and rear ends, said rear end of said bail having a locking head connected thereto by a narrower neck provided with shoulders at each end thereof, the width of said locking head being less than the transverse dimension of said opening head, said neck of the locking head being positioned in said branch of said opening and said locking head on the inner side of said wing and overhanging the longitudinal edge of said branch, said front end of said bail being secured in said socket so as to normally resiliently retain said locking head in engagement with said fastener elements, and a pull being retained in position by said bail for disengaging said locking head from said fastener elements.

2. A slider for a separable fastener comprising two wings and a spreader member interposed at their front ends, said wings and spreader being adapted to slide in contact with the fastener elements to engage and disengage same, said slider having a groove in its front end, one of said wings having a T-shaped opening in its rear end portion and so arranged that the stem of the T extends rearwardly, a one piece flat spring locking element having its front and rear ends extending inwardly, said front end of said spring having a reduced portion secured in said groove, said rear end of said locking element having a locking head adapted to pass through the head of said T opening and having a widthwise dimension greater than the width of the stem of said T opening, said head being extended through said opening and provided with shoulders which overhang the edges of the

stem of said T opening, said head having a projection thereon which is adapted to be resiliently held by the spring between the fastener elements to prevent the movement of the slider in the direction to disengage the fastener elements, and a pull member adapted to operate said slider and move said locking projection out of locking engagement with the fastener elements.

3. The method of making a slider for a separable fastener comprising the steps of forming a slider body with wings secured together at their front ends, forming an opening in the rear end of one wing having an enlarged head extending transversely of said wing and having a connecting branch opening extending rearwardly and longitudinally of said wing, forming a piece of flat spring metal into a combination bail and lock member having an end adapted to be secured to the front ends of said wings and having a locking head and a reduced portion formed on the other end of said member, longitudinally aligning the bail with the wing of the slider, extending the locking head through the head of the opening in the wing, moving the reduced portion of the bail adjacent to the locking head into the narrower branch opening with a generally rearward motion, and securing the other end of the bail to the front ends of the wings.

4. The method of making a slider for a separable fastener comprising the steps of forming a slider body with wings and a spreader member, forming an opening having a transversely enlarged head and a narrower branch in the rear end of one wing and so arranged that the branch extends longitudinally of the wing, forming a groove in the front end of the body of the slider so that it extends perpendicular to the plane of the wings, forming a U-shaped combination bail and lock member having a securing end on one end and a locking head and a reduced portion on the other end from flat spring metal, longitudinally aligning the bail with the wing of the slider, extending the locking head through the head of the opening in the wing, moving the reduced portion of the bail adjacent to the locking head into the narrower branch of the opening and the securing end of the bail into the groove in the front end of the body with a generally rearward motion, and fixing the securing end of the bail in the body of the slider.

5. The method of making a slider for a separable fastener comprising the steps of forming a slider body with wings and a spreader member, forming an opening having an enlarged head and a narrower branch in the rear end of one wing and so arranged that the branch extends longitudinally of the wing, forming a groove in the front end of the body of the slider so that it extends perpendicular to the plane of the wings, forming a U-shaped combination bail

and locking member with a notched out end on one end and a locking head and a contiguous reduced portion on the other end from flat spring metal, longitudinally aligning the bail with the wings of the slider, extending the locking head through the head of the opening in the wing while longitudinally aligned, moving the reduced portion of the bail contiguous to the locking head into the branch opening and the notched end of the bail into the groove in the front end of the body with a rearward motion, and bending the edges of the groove over the notched end of the bail to hold same in a fixed position.

10 6. The method of making a slider for a separable fastener comprising the steps of forming a slider body with wings and a spreader member, forming a T-shaped opening in the rear end of one wing and so arranged that the stem of the T extends longitudinally of the wing, forming a groove in the front end of the body of the slider so that it extends perpendicular to the plane of the wings, forming a U-shaped combination bail and locking member with a notched out end on one end and a T-shaped locking head and a contiguous reduced portion on the other end from flat spring metal, longitudinally aligning the bail with the wings of the slider, extending the locking head through the head of the opening in the wing, moving the reduced portion of the bail contiguous to the locking head into the stem of the T-shaped opening and the notched end of the bail into the groove in the front end of the body with a single motion, and bending the edges of the groove over the notched end of the bail to hold same in a fixed position.

15 7. The method of making a slider for a separable fastener comprising the steps of forming a slider body with wings and a spreader member, forming an L-shaped opening in the rear end of one wing and so arranged that the stem of the L extends longitudinally of the wing, forming a groove in the front end of the body of the slider so that it extends perpendicular to the plane of the wings, forming a U-shaped combination bail and locking member having a notched out end on one end and a locking head and a contiguous reduced portion on the other end from flat spring metal, longitudinally aligning the bail with the wings of the slider, extending the locking head through the head of the opening in the wing, moving the reduced portion of the bail contiguous to the locking head into the stem of the L-shaped opening and the notched end of the bail into the groove in the front end of the body with a single motion, and bending the edges of the groove over the notched end of the bail to hold same in a fixed position.

20 60 WILLIAM R. EPES.
